UNITED STATES PATENT OFFICE.

HERBERT E. PAGE, OF SYRACUSE, NEW YORK, ASSIGNOR TO UNITED STATES HOFFMAN MACHINERY CORPORATION, OF NEW YORK, N. Y., A CORPORATION OF DELAWARE.

GARMENT-PRESSING MACHINE.

Application filed March 10, 1923, Serial No. 624,146. Renewed September 18, 1926.

This invention pertains to garment pressing machines, and more particularly to that type wherein motor means is employed to effect a final heavy pressure which in certain 5 pressing operations is highly desirable. Such a press generally employs means, actuated by the operator to close the same, to secure the initial pressure upon the garment, the motor thereafter coming into operation to effect 10 the final or so-called heavy pressure upon the garment.

The present invention has for its main object the provision of means for automatically unlocking and opening the press after the 15 heavy pressure has been exerted and is released. Such means also embodies devices whereby manual opening or release of the press is prevented while the heavy pressure is on,—a point of manifest advantage. 20 Heretofore, in the operation of power presses, the operators have manually released or opened the press while the heavy pressure was being exerted, thereby causing damage to and breakage of the parts, as the press snaps 25 open under such conditions with considerable force. The structure is such, however, that the press may be opened by the operator without the actuation of the automatic mechanism, provided the power device has not 30 been brought into operation. In other words, an interlock is provided between the power mechanism and the release devices which prevents the manual actuation of the latter when the heavy pressure is effective.

35 A press embodying my invention is illustrated in the annexed drawings, wherein:

Fig. 1 is a side elevation, partly in section, with the press in its open position;

Fig. 2 a similar view, the press being closed 40 and the parts in position to effect heavy or final pressure;

Fig. 3 a detail sectional elevation of the combined interlock and kickoff or release mechanism;

45 Fig. 4 a front elevation of said parts with the main and release treadles broken away;

Fig. 5 a detail vertical sectional view on the line V—V of Fig. 3 illustrating more particularly the gravitating locking latch;

50 Fig. 6 a side elevation, partly in section, of the lower portion of the press, with the parts in the open position of the press; and

Fig. 7 a like view with the press closed, and final or heavy pressure applied.

In said drawings, 1 denotes the main frame 55 of the machine upon which is mounted a fixed buck 2. Pivotally mounted upon the upper end of an upward extension or arm 3 of the main frame is a lever 4 having secured at its forward end a press head 5. Said head and buck may be of any form and provided with the usual finish or covering according to the work being undertaken. The head is designed to be moved toward the buck 60 through the depression of a lever 6, provided at its forward end with a treadle 7, the lever being fulcrumed at its rear end upon a shaft 19 mounted in suitable bearing in the lower rear portion of the main frame 1. To effect the lowering of the head, lever 6 has connected to it a link 8, the upper end of which is connected to one element 9 of a toggle, the other element of which is designated by 10. Said latter element is pivotally connected at its outer end to the lower element 11 of a 65 second toggle, the upper element whereof is denoted by 12 and which in turn is pivotally connected to the lever 4. A yielding pressure element 13 is embodied in the toggle element 12. The lower toggle element 11 is 70 pivotally connected at 14 to a rocker member 15 fulcrumed upon the base of the machine at 16. Said member 15 is bifurcated at its inner end and straddles an annular bearing member 17 in which is mounted a cam 18 secured to shaft 19. In closing the press 75 through depression of the lever 6, link 8 straightens the toggle, composed of the elements 9 and 10, and carries the toggle 11, 12, from the position shown in Fig. 1 to a right 80 line position shown in Fig. 2, and through the straightening of these two toggles the lever 4 is rocked about its fulcrum and the head 5 caused to move downwardly and into contact with the goods or garment at such 85 time upon the buck 2. A coil spring 20 secured at one end to the frame 1 and at its opposite end to the pivotal connection between the link 10 and the link 11, serves to draw the toggles into their broken position, or, in other words, the spring is stressed when 90 the toggles are straightened, as in Fig. 2, and the moment the toggle 9, 10, is broken, the spring will tend to move the parts to the 95

position shown in Fig. 1, it being understood that the lever 4 is counterweighted, as at 21, so that the head may be moved upwardly without difficulty. Cam 18 is designed to 5 actuate the rocker 15 when heavy pressure is to be applied to the garment being pressed. In Fig. 1 the cam is in its lowest position and so remains when the press is initially closed through the operation of the lever 6. After 10 the head is initially closed, or, in other words, initial pressure is effected between the pressing elements, the operator throws in a switch, shortly to be described, and through a motor and suitable gearing, causes the cam to rotate from the position shown in Fig. 1 to that shown in Fig. 2, thus lifting the outer end of the rocker and applying a direct thrust to the lever 4 through the then straightened toggle elements 11, 12, and exerting such 15 thrust through lever 4 to the head 5.

The motor, indicated by 22, drives a worm 23 mounted in a suitable housing and intermeshing with a worm gear 24 secured to a shaft 25, which latter carries a pinion 26. 20 Said pinion meshes with a gear 27 secured upon the shaft 19, which, as above noted, likewise carries the cam 18. It will thus be seen that actuation of the gear train through the motor 22 will cause a movement of the 25 rocker 15 and apply heavy pressure, as above noted, and likewise when the rocker is lowered, relieve such pressure. To control the operation of the motor, shaft 19 carries a crank arm 28 and attached thereto is 30 a pitman 29, the upper end of which has pivotally secured thereto a rod 30 mounted in lugs or ears 31 and 32 formed upon a switch box 33. A double throw switch is 35 mounted in the box and a lever 34 is secured to the outer end of the switch actuating 40 shaft 35. Said arm 34 has secured to its free end one end of a spring 36, the opposite end of the spring being secured to a collar 37 fixed to the rod 30 and movable therewith. 45 Stops 38 and 39 are formed upon the face of the switch box and serve to limit the upward and downward throw of the switch arm 34. A sliding rod 40 extends outwardly beneath the table of the machine, the inner 50 end of the rod being mounted in a suitable bracket 41 between the arms of which there is mounted a spring 42 which normally draws the rod inwardly and projects its inner end into the path of the outer end of the switch arm 34. In other words, the inner 55 end of the member 40 acts as an arresting stop for the switch arm and normally holds the same in such position that the switch is open under certain conditions. The switch 60 contacts, not shown, are connected through suitable wiring, as 43, with the motor 22.

When the press is closed an initial pressure is effected and the cam 18 is in its low position, as shown in Fig. 1. The rod 30 is likewise in its low position, and consequently the

switch arm 34 is held against the upper face of the rod 40, or in a neutral position. By then pulling the rod 40 outwardly the switch arm is released, and the spring 36, which is then under tension, pulls the arm downwardly and establishes the current passing to the motor. The motor then comes into operation, turning the shaft 19 and rotating the cam therewith, thereby raising the rocker 15 and applying direct thrust to the main or 70 pressure exerting toggle, 11, 12. As the shaft 19 rotates, the pitman 29 is carried from the position shown in Fig. 6 to the position shown in Fig. 7, moving rod 30 upwardly and carrying the spring up with it, so that as it passes the center of the shaft 35, it will draw the switch arm 34 upwardly from its position against the lower stop 39 to the position shown in Fig. 2, the arm contacting the inner end of the rod 40, arresting further 80 movement of the arm and consequently leaving the switch in its open position and bringing the parts to rest by interruption of the current. This will leave the cam in the position shown in Fig. 2, with the heavy 85 pressure exerted through the main toggle to the movable press head. So long as the rod 40 stays in and holds the switch arm against further movement such heavy pressure will be maintained.

This switch mechanism is not of my invention and any other automatic switching mechanism may be employed. While the heavy pressure is on, as indicated at the outset, it is desirable that the operator be prevented from releasing the head and allowing the parts to jump open, for the release of such pressure through manual operation is likely to cause damage and breakage of the parts.

A bracket 42 is secured to the lower front portion of the frame of the machine, and pivotally attached thereto is a supplemental or kick-off pedal 43 provided with an upstanding arm 44. Said arm 44 lies along side of a locking lever, denoted generally by 45, which latter is provided with an outwardly extending pin 46 which stands in front of the arm 44 of the kick-off lever or pedal. The locking lever 45 is fulcrumed at 47 to a bracket 48 secured to the frame 1, and its lower end is normally drawn inwardly by a spring 49 interposed between its upper end and the frame of the machine. The lower end of said locking lever is cut away at its inner side, forming a locking shoulder 50 adapted to ride over and engage a roller 51 secured upon the side face of the main treadle lever 6 when said treadle lever is depressed or brought to the position shown in Figs. 2 and 3. When the machine is being operated by the operator, without the exertion of the final heavy pressure, the operator may, upon depressing the kick-off 100 pedal 43, force the lower end of the locking 105

lever 45 outwardly through contact of the arm 44 and the pin 46, thereby permitting the main lever 6 to be moved upwardly under the stress of the spring 20 and also 5 through the buffer spring 52.

Lever 45 is provided with an inwardly extending arm 53 having at its inner end a notched or shouldered portion 54 with which cooperates the upper end of a gravitating latch 55, said latch being pivoted at 56 upon the main frame and provided with a counter-weighted lower end 57 which tends normally to throw the upper end of the latch to the left (Fig. 3) and into engagement with the locking shoulder or notch 54. Said latch is also provided with an inverted U-shaped guide 58 (see more particularly Fig. 5) through which extends a rod 59, said rod being supported for endwise movement in an eye-bolt 60 secured to and carried by the inner end of the arm 53. The rear end of the rod 59 is pivotally connected to an upwardly extending arm or lever 61 formed as an integral portion of the rocker element 15, and movable therewith as the same is rocked about its supporting shaft 16. Thus an endwise movement is imparted to the rod 59 each time the rocker is actuated. The rod carries a stop block or collar 62 located adjacent the inner face of the U-shaped guide formed upon the gravitating lock or latch 55, the outer end of the rod terminating adjacent a swinging pawl or abutment 63 pivoted at 64 upon the locking lever 45. A pin 65 maintains the swinging abutment against movement in one direction beyond a predetermined limit, but allows it to swing clockwise when the rod 59, as will herein-after appear, is elevated and moves rearwardly, and at such time contacts the gravitating pawl 63.

The operation of the power mechanism and kick-off is as follows:

Assuming that the press has been closed by the operator by the depression of the treadle 7 which straightens the two toggles and brings the head 5 down upon the buck, the parts assume the position above described and as shown in Fig. 2. So long as the rod 40 remains in, as shown in said figure, the switch is held out of operation and the rocker 15 remains elevated, owing to the fact that the cam 18 is turned upwardly or is in its highest position. The heavy pressure which then obtains, may remain on as long as desired and the operator may pass to another machine, position the garment thereon, and close the press. He can then return to the first machine and by merely pulling out the rod 40 release the switch arm 34, which, under the action of the spring 36 is drawn upwardly, again closing the circuit and bringing the motor into operation. This rotates the cam and releases the heavy pressure, the rod 30 at such time moving downwardly,

or to the position shown in Fig. 1, and when the spring 36 passes the center of the switch shaft 35 the switch arm will be drawn downwardly, breaking the contact. This breaking of the contact or circuit takes place 70 when the cam is in its lowest position with the rocker likewise lowered. The motor comes to rest almost immediately after the circuit is broken, and the parts are so timed that this is effected when the cam 18 comes to the position shown in Fig. 1 with the rocker thrown downwardly. As the rocker moves downwardly the arm 61 moves to the right, forcing the rod 59 forwardly causing the stop collar 62 to contact the U-shaped 75 guide 58, and forcing the upper end of latch 55 out of engagement with the shoulder 54 of the inwardly extending arm 53. Thus the lever 45 is released in so far as locking of the latch is concerned, and upon a further forward movement of the rod 59 its end contacts the gravitating stop 63 and swings the lower end of the lever 45 outwardly thereby causing the shouldered portion 50 to move off of the roller 51, thus releasing the main treadle lever 6. The press then opens automatically under the action of the springs, as hereafter described.

After the press is closed by depressing the treadle and the motor circuit is again established through the pulling out of the rod 40, the cam is rotated and the rocker elevated. During such upward movement of the rocker 15 the arm 61 is thrown rearwardly, drawing with it the rod 59, the parts coming to the position shown in Fig. 2. It is to be kept in mind that when the lever 6 is depressed to its full extent the locking lever 45 assumes the position shown in Fig. 3, and as a consequence the gravitating abutment or pawl 63 stands in the way of the elevation of the rod 59 which is carried up from the position shown in Fig. 1 to that shown in Figs. 2 and 3 by the eye 60 as the lower end of the lever 45 is swung inwardly to lock the treadle in place. It is for this reason that the member 63 is pivoted so as to allow the rod to move upwardly and then rearwardly to the position shown in Figs. 2 and 3.

The member 55 is, in effect, a lock for the locking lever or locking means 45. In other words, it is a lock for the lock, and prevents the release of the actuating lever 6 when the heavy pressure is to be exerted.

What is claimed is,—

1. In a press, the combination of two relatively movable pressing elements; means adapted to be actuated by the operator to move said elements into pressing relation; locking means to hold the aforesaid means against release movement; means under the control of the operator to release the locking means; power actuated means for exerting heavy pressure between the pressing ele- 120

- ments; and mechanism actuated by the power means to lock the locking means against release by the operator.
2. In a press, the combination of two relatively movable pressing elements; means adapted to be actuated by the operator to move said elements into pressing relation; locking means to hold the aforesaid means against release movement; means under the control of the operator to release the locking means; power actuated means for exerting heavy pressure between the pressing elements; and mechanism actuated by the power means to lock the locking means against release by the operator and to thereafter unlock the locking means.
3. In a press, the combination of two relatively movable pressing elements; means adapted to be actuated by the operator to move said elements into pressing relation; locking means to hold the aforesaid means against release movement; means under the control of the operator to release the locking means; power actuated means for exerting heavy pressure between the pressing elements; and mechanism actuated by the power means to lock the locking means against release by the operator, said mechanism, upon release of the heavy pressure, acting to unlock the locking means and to move the same to release position.
4. In a press, the combination of two relatively movable pressing elements; means adapted to be actuated by the operator to move said elements into pressing relation; a locking lever adapted when the press is closed to normally hold the same in such condition; means under the control of the operator to release said locking lever; power actuated means to apply heavy pressure to the movable pressing elements when the same have been initially closed; and means associated with and actuated by said power means for locking the lever against movement when heavy pressure is being exerted and thereafter upon release of the heavy pressure through the operation of the power mechanism, to move the lever from its locking position.
5. In a press, the combination of a buck; a head; a lever supporting said head; means for swinging said lever comprising toggle mechanism; a treadle lever connected to said toggle mechanism and adapted when moved downwardly to straighten the toggle mechanism and lower the head into pressing relation with the buck; a pivoted lever cooperating with the treadle lever to normally hold the same in its depressed position; power actuated means for exerting a heavy pressure through the toggle mechanism; a lock for the lever adapted to hold the same in its locked relation to the treadle lever; and means associated with the power means for releasing said lock and moving the lock-
- ing lever to its released position upon movement of the power means to release position.
6. In a press, the combination of a buck; a head; a pivoted lever to which the head is attached; toggle mechanism for swinging the lever and bringing the head into pressing relation with the buck; a treadle lever; connections intermediate said treadle lever and the toggle mechanism for actuating the latter in one direction; a locking lever, the lower end whereof is adapted to cooperate with the treadle lever to hold the same in its depressed condition with the head in pressing relation to the buck; a second treadle; connections between said second treadle and the locking lever whereby the latter may be disengaged from the treadle lever to release the same; a gravitating latch for said locking lever adapted to hold the same in its locked relation with reference to the treadle lever; power actuated means to exert heavy pressure upon the lever and to the head carried thereby, through the toggle mechanism; and means working in timed relation with said power means to first release the latch and to thereafter release the locking lever upon a release movement of the heavy pressure applying means.
7. In a press, the combination of a buck; a pivoted lever; a head carried thereby; toggle mechanism for swinging said lever and bringing the head into pressing relation with the buck; a treadle lever; connections intermediate the toggle mechanism and the treadle lever for swinging the lever; a locking lever, the lower end of which is provided with a shouldered portion; a roller mounted upon the treadle lever adapted to coact with said shouldered portion; a spring serving normally to throw said lever into engagement with the roller; a release treadle cooperating with a member carried by the locking lever; an arm extending rigidly from the locking lever; means for applying heavy pressure to the press through the toggle mechanism; a gravitating lock adapted to lock the locking lever against movement when the heavy pressure is exerted; a rod associated and moveable with said heavy pressure applying means; a supporting element for said rod, said element extending downwardly from the arm aforesaid; and a stop secured to the rod and adapted to coact with the lock to move the same to release position as the heavy pressure applying means is brought to release position.
8. In a press, the combination of a buck; a pivoted lever; a head carried thereby; toggle mechanism for swinging said lever and bringing the head into pressing relation with the buck; a treadle lever; connections intermediate the toggle mechanism and the treadle lever for swinging the lever; a locking lever, the lower end of which is pro-

- vided with a shouldered portion; a roller mounted upon the treadle lever adapted to coact with said shouldered portion; a spring serving normally to throw said lever into engagement with the roller; a release treadle cooperating with a member carried by the locking lever; an arm extending rigidly from the locking lever; means for applying heavy pressure to the press through the toggle mechanism; a gravitating lock adapted to lock the lever against movement when the heavy pressure is exerted; a rod associated and movable with said heavy pressure applying means; a supporting element for said rod, said element extending downwardly from the arm aforesaid; a stop secured to the rod, adapted to cooperate with the lock to release the same; and an abutment carried by the locking lever, said abutment adapted to coact with the end of the rod when said rod is moved endwise during the release of the heavy pressure applied to the press by the heavy pressure applying mechanism.
- 25 9. In a press, the combination of two relatively movable pressing elements; means adapted to be actuated by the operator to move said elements into pressing relation; locking mechanism to hold the aforesaid means against release movement; means under the control of the operator to release the locking mechanism; power actuated means for exerting heavy pressure between the pressing elements after they have been brought to their initial closed position, including an electric motor; circuit closing means for said motor; and means actuated by and working in timed relation with the power actuated means for moving the circuit controlling means to make and break the circuit.
- 30 10. In a press, the combination of two relatively movable pressing elements; means
- adapted to be actuated by the operator to move said elements into pressing relation; locking mechanism to hold the aforesaid means against release movement; means under the control of the operator to release the locking mechanism; power actuated means for exerting heavy pressure between the pressing elements after they have been brought to their initial closed position, including an electric motor; circuit closing means for said motor; and means actuated by and working in timed relation with the power actuated means for moving the circuit controlling means to make and break the circuit; and means under the control of the operator to arrest the movement of the circuit controlling means whereby the circuit may be held open and the press elements allowed to remain in their closed position with the heavy pressure exerted thereon.
- 35 11. In a press, the combination of two relatively movable pressing elements; means adapted to be actuated by the operator to move said elements into pressing relation; locking mechanism to hold the aforesaid means against release movement; means under the control of the operator to release the locking mechanism; power actuated means for exerting heavy pressure between the pressing elements after they have been brought to their initial closed position, including an electric motor; circuit closing means for said motor; and means actuated by and working in timed relation with the power actuated means for moving the circuit controlling means to make and break the circuit; and means under the control of the operator to arrest the movement of the circuit controlling means whereby the circuit may be held open and the press elements allowed to remain in their closed position with the heavy pressure exerted thereon.
- 40 12. In a press, the combination of two relatively movable pressing elements; means

In testimony whereof I have signed my name to this specification.

HERBERT E. PAGE.
